[57] CLAIM

The ornamental design for a detachable passenger compartment for a golf cart, as shown and described.

DESCRIPTION

FIG. 1 is a perspective view of a detachable passenger compartment for a golf cart showing my new design; the broken lines are for illustrative purposes only and form no part of the design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a front elevational view thereof; and

FIG. 7 is a rear elevational view thereof.
